US00D747758S

(12) **United States Design Patent**
Lee et al.

(10) **Patent No.:** **US D747,758 S**
(45) **Date of Patent:** **** Jan. 19, 2016**

(54) **GLASSES**(71) Applicant: **TRIMAX SAFETY CORP.**, Tainan (TW)(72) Inventors: **Shih-I Lee**, Tainan (TW); **Ching-Hsiu Chan**, Tainan (TW)(73) Assignee: **Trimax Safety Corp.**, Tainan (TW)(***) Term: **14 Years**(21) Appl. No.: **29/512,770**(22) Filed: **Dec. 22, 2014**(51) LOC (10) Cl. **16-06**

(52) U.S. Cl.

USPC ..... **D16/312**(58) **Field of Classification Search**

Primary Examiner — Susan Moon Lee

(74) Attorney, Agent, or Firm — Che-Yang Chen; Law Office of Michael Chen

(57) **CLAIM**

The ornamental design for glasses, as shown and described.

DESCRIPTION

FIG. 1 is a front perspective view of glasses, showing our new design;
 FIG. 2 is a rear perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top view thereof; and,
 FIG. 8 is a bottom view thereof.
